An Improvement in Screens

Letters Patent No. 23356. Granted August 1866.

Design for a Coal Screen.

The shade or screen in these letters patent and making part of the same shall whom it may concern:

Be it known that we, Martin, C. B. & C. C. Currie, of Philadelphia, County of Philadelphia, State of Pennsylvania, have invented or introduced a new and useful shade or screen, as will more fully appear in the accompanying drawing, with the following description of the same to form a full, clear and exact description of the said design.

In the accompanying drawing

Fig. 1 represents the front plate of the "Planter's premium" coal stove.

Fig. 2 represents the side plates only.

Fig. 3 the back plate.

To the front plate, which is bordered by a plain edge, are hinged two side plates.

The side plates are made of cast iron, and are made so as to be parallel to each other, and near each side edge there is a horizontal aperture.

Each door 3 is bordered by a plain moulting, and the door is thin. The moulting is a narrow border, being in composition of various figures

In the centre of which is a central panel containing a cross-shaped figure.

Both edges of the side panels in plain moulding and buttments are in the form of lotus & each of which is bordered by a plain moulding. There is a plain horizontal edging similar to the design in the door B.3.

In the centre of the door B.3 is a central panel in white lacquer containing figures, and of the central side door it is a plain panel with a narrow moulded edging.

In the centre of the panel of lacquer are two figures seated and in a car which forms part of the door B.3 figures are the two deities Planter's Predecessors.

The back panel is bordered by a plain moulding and in the centre are two slender panels which are decorated in the same manner as the door B.3.

The design for the front of the Planter's Predecessor's door is substantially the same as that by the arrangement of the two figures.

The figures are in the same position as those in the door B.3. The figures are in the same position as those in the door B.3.
